UNITED STATES PATENT OFFICE.

JAMES ALLEN HUGGINS, OF FLORENCE, SOUTH CAROLINA.

SUBSOIL-PLOW.

1,185,324.

Specification of Letters Patent. Patented May 30, 1916.

Application filed January 27, 1914. Serial No. 814,729.

To all whom it may concern:

Be it known that I, JAMES ALLEN HUGGINS, a citizen of the United States, residing at Florence, in the county of Florence and State of South Carolina, have invented certain new and useful Improvements in Subsoil-Plows, of which the following is a specification.

This invention relates to a subsoil plow, and the principal object of the invention is to provide an improved means for constructing a subsoiler which will permit of vertical adjustment of the point-carrying standard; to provide improved means for pivotally mounting the subsoiler beam; and to also provide improved means for limiting the pivotal movement of the beam in one direction.

Another object of the invention is to so connect the standard and subsoiler beam that the standard may be easily adjusted and securely held in the adjusted position.

Another object of the invention is to provide means for permitting transverse movement of the standard after being adjusted.

Another object of the invention is to so construct the front-end portion of the subsoiler beam that when desired, the subsoiler may be easily removed from the plow.

Another object of the invention is to so construct the brace which is carried by the main plow beam and engages the subsoiler beam that the brace may be longitudinally adjusted, and to so construct the free-end portion of the brace that it will engage the subsoiler beam at right angles and prevent the subsoiler from rising when striking hard places in the soil.

This invention is illustrated in the accompanying drawings wherein—

Figure 1 is a side elevation of the subsoil plow with the point of the main plow partly broken away; Fig. 2 is a longitudinal sectional view taken along the line 2—2 of

Fig. 1; Fig. 3 is a sectional view taken along the line 3—3 of Fig. 1; Fig. 4 is a view taken along the line 4—4 of Fig. 1 and showing the bracing bar in top plan; Fig. 5 is a perspective view of the standard and rear-end portion of the beam for the subsoiler.

The main plow structure comprises the plow beam 10, digging point 11, handle 12, and handle braces 13. The point 11 is secured to the beam 10 by means of the bolts

14 and 15 which extend through the plow beam 10 to engage a U-shaped housing 16.

The bolt 14 only passes through the inner wall of the housing 16, but the bolt 15 extends entirely through the housing and forms a pivot pin for the beam of the subsoiler.

The subsoiler is provided with a standard 17 which carries the digging point 18 and fits against the front face of the vertically-extending rear arm 19 of the beam indicated in general by the numeral 20. This beam 20 is carried across the upper end of the standard 17 to form a bridge 21 from which there extends the diagonally-extending arm 22, the lower end 23 of which extends horizontally. Diagonal bracing strips 24 extend from the rear arm of the beam 20 to the diagonally-extending arm 22 and are positioned upon opposite sides of the standard 17 so that the standard will be prevented from moving transversely. A collar 25 passes around the standard 17 and rear arm 19 of the beam 20, is securely connected to the standard 17 by means of the bolts 26 and 27, and is adjustably connected with the arm 19 by means of a bolt 28 which passes through one of the openings 29 formed in the arm 19. A yoke 30 straddles the bridge 21 and is rigidly secured to the collar 25 by means of the bolt 26 and adjustably connected with the bridge 21 by means of a bolt 31 which passes through the bridge 21 and through a selected set of the openings 32 formed in the yoke. By this arrangement the standard 17 may be vertically adjusted by removing the bolts 28 and 31 and after sliding the standard 17 along the arm 19 to the desired place, replace the bolts. The standard 17 will then be securely held in the new position. If desired, the yoke 30 may be done away with and the standard held in place by the collar 25 alone; or if preferred, bolt 28 may be removed and standard 17 held in position by yoke 30 and bolt 31.

The forward section 33 of the subsoiler beam 20 is pivotally mounted upon the bolt 15 within the housing 16 and is provided with a hinge ear 34 through which there passes a bolt 35 which is carried by hinge ears 36 of the extension 37. The extension 37 is secured to the forward portion 23 of the diagonally-extending arm 22 by means of bolts 38, and it will be seen that the rear arm of the beam 20 will be hinged to the front section 33 and thus permitted to have horizontal pivotal movement. By having

the beam of the subsoiler pivotally connected with the beam of the main plow, as clearly shown in Figs. 1 and 2, the subsoiler can be caused to dig into the bottom of the furrow made by the main plow 11 as deep as desired. A bail 13' connected with handles and braces is provided to prevent undue horizontal movement.

It is desired to prevent the subsoiler from rising upon striking hard ground, and therefore the adjustable combination brace shown in Figs. 1 and 4 has been provided. This brace comprises the front and rear bars 39 and 40 which are removably connected together by means of the bolts 41. The front bar is pivotally mounted upon the bolt 42 which connects the handle braces 13 with the main plow beam 10 to permit the brace for the subsoiler beam 20 to be moved to bring the bridge 43 of the head 44 into engagement with the diagonal arm 22 of the beam 20. This head 44 is provided with converging arms 45 and 46 which extend from the head 43 and have their end portions 47 and 48 secured to the hook-shaped end portion 49 of the bar 40 by means of rivets 50. The head 44 engages the diagonal arm 22 at right angles thereto and is of such width that the subsoiler beam 20 can not move out of engagement with the head. To disengage the subsoiler from the ground, diagonal arm 22 may be placed in hook 49.

In the operation of this device the plow 35 may be used as an ordinary plow by removing the subsoiler and subsoiler brace; or if desired, the rear arm 40 may be removed from the front arm 39 and the rear section of the subsoiler beam 20 may be removed 40 from the forward section 33. This is done by removing the bolts 41 and hinge bolt 35. When it is desired to use the subsoiler, the subsoiler is connected with the plow as shown in Fig. 1 and the standard 17 is adjusted so that the point 18 will cut into the bottom of the furrow the desired depth. After the standard has been adjusted, the brace is lowered to bring the head 44 into engagement with the diagonal arm 22 of 50 the subsoiler beam. The subsoiler beam will then be prevented from rising in case the point 18 strikes hard dirt. By having the rear section of the subsoiler beam pivotally mounted for horizontal pivotal movement the subsoiler will be permitted to have transverse movement, but it should be noted that the bail 13' for the subsoiler beam will prevent undue horizontal pivotal movement when the subsoiler is in use, and thus prevent the subsoiler from dragging and being wrenching out of shape when taking the main plow from the furrow.

I have thus provided a subsoil plow in 65 which the subsoiler may be easily connected and disconnected. I have provided a sub-

soiler which is so constructed that the standard may be vertically adjusted and securely held in the adjusted position. I have also provided a subsoiler which will be permitted to freely move pivotally, but 70 which is prevented from vertical movement in one direction by an improved brace pivotally connected with the main plow beam and engaging the subsoiler beam at right angles thereto. It should also be noted 75 that this subsoiler is so constructed that it may be used without danger of breaking or easily getting out of order since the parts are very few and very simple in construction. 80

What is claimed is:

1. The combination of a plow structure and a subsoiler including a standard, a beam, a collar adjustably connecting said standard with said beam, a yoke carried by 85 said collar and adjustably connected with said beam, and means for connecting said beam with said plow structure.

2. The combination of a plow structure and a subsoiler connected therewith, said subsoiler including a beam, a standard, a collar slidably connecting said standard with said beam, and means carried by said collar for releasably holding said standard in an 90 adjusted position.

3. A subsoiler including a standard, a beam having its outer end portion extending parallel to said standard and downwardly with its inner end portion extending at substantially right angles to its outer end portion, and means for connecting said standard with said beam. 100

4. The combination of a plow structure including a beam, handles, braces extending from said handles to said beam, a subsoiler including a beam having its inner-end portion connected with said plow beam, and a bar carried by said plow beam and provided with a transversely-extending head to 105 engage the beam of the subsoiler.

5. The combination of a plow structure including a plow beam, a subsoiler including a beam connected with said plow beam, and a brace for said subsoiler beam comprising an inner bar pivotally connected with said plow beam, an outer bar secured to said inner bar and provided with a hook-shaped outer-end portion, and a head carried by the outer-end portion of said outer bar and provided with a bridge engaging the beam of said subsoiler and having arms leading therefrom in converging relation and secured to the hook-shaped outer end portion of said outer arm. 115

6. The combination of a main plow structure including a plow beam, a subsoiler including a beam connected with the plow beam for vertical pivotal movement and provided adjacent its inner end with means for 120 125 130

permitting horizontal pivotal movement, one section of the subsoiler beam being upwardly inclined and extending from the inner end portion of said plow beam, and a brace pivotally connected with said plow beam and provided with an enlarged head extending at right angles to the body portion of the brace engaging the inclined section of the subsoiler beam to prevent vertical pivotal movement of the subsoiler in one direction but permit horizontal pivotal movement of the subsoiler.

7. A subsoiler including a beam having a vertically-extending outer end portion and being then provided with a horizontally-extending bridge having a diagonally-extending arm extending downwardly there-

from and provided with a horizontally-extending inner-end portion, digging means adjustably connected with the outer-end portion of said beam and positioned between the outer end portion and diagonally-extending arm of the beam, and bracing strips positioned upon opposite sides of said digging means and having their end portions secured to the lower outer end portion of said beam and to the intermediate portion of the diagonal arm of said beam.

In testimony whereof I affix my signature in presence of two witnesses.
